(57) **CLAIM**

We claim the ornamental design for a golf club head, as shown and described.

DESCRIPTION

FIG. 1 is a perspective view of a golf club head, as viewed from the rear and one side thereof, according to one embodiment.

FIG. 2 is a rear elevation view of the golf club head of FIG. 1.

FIG. 3 is a top plan view of the golf club head of FIG. 1.

FIG. 4 is a front elevation view of the golf club head of FIG. 1.

FIG. 5 is a bottom plan view of the golf club head of FIG. 1.

FIG. 6 is a side elevation view of the heel of the golf club head of FIG. 1; and,

FIG. 7 is a side elevation view of the toe of the golf club head of FIG. 1.

The dashed lines in the drawings are for illustrative purpose only and form no part of the claimed design.
